Inventor,

William Huesy

United States Patent Office.

WILLIAM HUEY, OF GALENA, MARYLAND.

Letters Patent No. 66,346, dated July 2, 1867.

FRUIT-BOX.

The Schedule referred to in these Letters Patent and making part of the same.

TO ALL WHOM IT MAY CONCERN:

Be it known that I, WILLIAM HUEY, of Galena, Kent county, Maryland, have invented a new and useful Box for Fruit or Vegetables; and I do hereby declare that the following is a full and exact description of the same, reference being had to the annexed drawings, forming part hereof, and to the letters of reference marked thereon, in which drawings—

Figure 1 is a perspective of two boxes one within the other as they are packed for transportation when empty.

Figure 2 is a vertical section of the same on the line *xy* of fig. 1.

Figure 3 is a perspective of the lid.

Figure 4 is a perspective of the lock, full size.

The size of the boxes may be varied at will, but they should be of uniform size, or all of any one set uniform, so as to pack well one within another when empty, as represented in fig. 1.

In the drawings, *a* are thin slats of wood; *b* is a wooden rim to which the slats *a* are fastened at top. The rim *b* is grooved out on the under side, forming a rabbet of such depth that the ends of the slats *a* come about flush with the inside of the rim. The rim is strengthened with rivets *c*, fig. 1, one at each corner. The slats *a* are fastened at their lower ends to a wooden bottom, *d*. The corners *e* are each of one piece, they being formed by rabbeting a solid block to the thickness of the slats. The middle slats *f* on two opposite sides of the box are notched on the inside as at *g*, fig. 1, and each of the other two opposite sides of the box is provided with a lock, *H*, which consists of a plate, *h*, a plate, *i*, and a spring, *l*, the plate *i* being hooked at each end in opposite directions and being attached to plate *H* by a rivet, *K*. The spring *l* may be either India rubber or a metallic spiral, as in fig. 2, or flat spring. A key-hole, *m*, is made in the plate *h*. *n*, fig. 2, is the key, which is simply a piece of wire. *p*, fig. 3, is the lid, which is made of slats fastened to cross-pieces, and provided with a staple, *q*, and a lip, *r*, which take into the hooks of the plate *i* and thus fasten the lid on the box. If desired a lip may be substituted for the staple *q*. When empty, these boxes, to any number desired, may be packed one within another, as represented in figs. 1 and 2. When thus packed a lid is applied to the last of the series, and all the boxes fastened together by the automatic action of the locks. The remaining lids are packed separately. All the parts respectively of which the boxes are composed are made so as to be interchangeable.

It is obvious that the slats composing box or lid may be varied in number and size. The locks described may be applied to baskets.

Having thus described my invention, I claim, and desire to secure by Letters Patent—

1. As a new article of manufacture, the fruit and vegetable-box with the lid, all constructed substantially as set forth.

2. The lock *H*, composed of the plate *h*, with a key-hole, the hooked plate *i*, and the spring *l*, arranged substantially as set forth.

3. The slats *a*, notched slats *g*, and rabbeted corners *e*, in combination with the rabbeted rim *b* and rivets *c*.

4. The slats *a*, notched slats *g*, rabbeted corners *e*, and locks *H*, in combination with the lid *p*, substantially as set forth.

WILLIAM HUEY.
